[57] CLAIM

The ornamental design for a weeder tool, as shown and described.

DESCRIPTION

FIG. 1 is a perspective view of a weeder tool showing my new design;

FIG. 2 is a right side elevational view thereof, the left side being a mirror image of that shown;

FIG. 3 is a rear elevational view thereof;

FIG. 4 is a top plan view thereof; and

FIG. 5 is a right side of an alternate embodiment thereof, the only difference residing in the angle of the handle portion.

FIG. 2

FIG. 3

FIG. 5
